[57] CLAIM

The ornamental design for a buoyant eyeglass holder, as shown and described.

DESCRIPTION

FIG. 1 is a perspective view of the buoyant eyeglass holder embodying the design of the present invention; FIG. 2 is a front elevational view thereof in a curled configuration adapted to connect to ear pieces of a user's glasses;

FIG. 3 is a rear elevational view thereof;

FIG. 4 is an end elevational view thereof, the end opposite being a mirror image of the end shown in FIG. 4; and,

FIG. 5 is a side elevational view thereof, the side opposite being a mirror image of the side shown in FIG. 5. It is noted that the device is made of a material that floats in water with sufficient buoyancy to keep glasses attached thereto afloat.

FIG. 1.

FIG. 3.

FIG. 5.
